UNITED STATES PATENT OFFICE.

WINFIELD S. LIVENGOOD, OF KANSAS CITY, MISSOURI, ASSIGNOR TO ANDREW A. KRAMER, OF KANSAS CITY, MISSOURI.

TRUCK-HOIST.

1,312,489.

Specification of Letters Patent. Patented Aug. 5, 1919.

Application filed May 28, 1918. Serial No. 237,024.

To all whom it may concern:

Be it known that I, WINFIELD S. LIVENGOOD, a citizen of the United States, residing at Kansas City, in the county of Jackson 5 and State of Missouri, have invented certain new and useful Improvements in Truck-Hoists; and I do declare the following to be a full, clear, and exact description of the invention, such as will enable others skilled 10 in the art to which it appertains to make and and use the same, reference being had to the accompanying drawings, and to the letters and figures of reference marked therein, which form a part of this specification.

15 My invention relates to dump trucks and more particularly to a hoist whereby a truck body may be actuated on a pivotal mounting to an inclined position to facilitate the unloading of material therefrom; the principal object of the invention being to provide a manually operated hoist of this character wherein the hoisting mechanism is so arranged that a minimum amount of space 20 will be utilized for the hoist.

25 A further object of the invention is to provide a hoist comprising pivotally mounted standards and means whereby they are normally retained perpendicularly to the truck frame but are allowed to move so as to practically retain a perpendicular relation to the truck body as the latter moves to and from an inclined position and relieve the standards of the lateral strain that would result if they were fixed perfectly 35 rigid on the truck frame.

A still further object of the invention is to provide a latch mechanism whereby the hoist parts may be locked to hold the truck body at any suspended position and comprising a brake shoe that may be moved on releasing the latch to cause a braking effect and thereby ease the lowering of the truck body to loading or normal position.

In accomplishing these objects, I have provided improved details of structure, the preferred forms of which are illustrated in the accompanying drawings, wherein:

Figure I is a side elevation of a truck equipped with a hoist constructed according 50 to the present invention.

Fig. II is a front view of the hoist mechanism.

Fig. III is a back view of the same, parts

being broken away and in section for better illustrating the hoist gearing.

55

Fig. IV is a transverse vertical section of the same on the line IV—IV, Fig. III.

Fig. V is an enlarged sectional view illustrating the fastening and winding of the cable on the hoisting drum.

60

Fig. VI is an enlarged detail view, partly in section illustrating the hinged mounting of the lower end of the hoist frame and one of the springs for yieldingly retaining the same in upright position.

65

Fig. VII is an enlarged side view of the hoist, the ratchet lock and brake mechanism.

Fig. VIII is a sectional view of the same parts, illustrating the brake shoe.

Fig. IX illustrates a type of hoist frame 70 used for a single cable device.

Referring more in detail to the drawings:

1 designates an automobile truck of any ordinary type of construction, having a chassis comprising longitudinally extending, 75 spaced side beams 2—2' whereon, at opposite points at the rear of the chassis, bearing members 3 are fixed; the latter are adapted to receive trunnions 4 extending from adjacent the rearward ends of a truck 80 frame 5 whereon a truck bed 6 is mounted so that the said frame and bed may be moved, in a pivotal manner to an inclined position and material within the bed may be delivered from the rear end thereof.

85

The truck bed 6 terminates a short distance from the vehicle seat 7, and intermediate the seat and bed, a hoist mechanism constructed according to the present invention, is mounted; the latter being supported centrally between the side beams 2—2' by a pair of inwardly facing angle beams 8—8' mounted transversely across the frame and resting at their opposite ends on blocks 9—9' which in turn are fixed on the side rails 95 2—2' by means of U-bolts 10 that inclose the ends of the blocks and are extended about the said beams and through the ends of anchor plates 11 and are equipped with nuts 12 which may be tightened against the 100 plates to hold the blocks securely in place on the frame.

95

Fixed within the angle members 8—8' is the hoist frame, the same comprising spaced, vertically extending standards 15—15' which 105 form the sides of the hoist frame and

at their upper ends support the opposite ends of a transverse shaft 16, whereon spaced sheave wheels 17-17' are revolvably mounted. The hoist frame is normally retained in this vertical position by means of a pair of coil springs 18-18' which are mounted about bolts 19-19' fixed pivotally at their lower ends in apertures 20 in the blocks 9-9' and extended upwardly between the ends of the beams 8-8'; the said springs bear at their upper ends against washers 21 seated against the heads 22 at the upper ends of the bolts and at their lower ends bear against plates 23 extending between and fixed to the ends of the beams 8-8'; the plates being provided with apertures 24 through which the bolts may extend.

With this arrangement it is apparent that the bolts 18-18' will hold the frame in functional position and that the pressure of the two coil springs will yieldingly hold the same substantially in vertical position but will allow it to move pivotally on the corner of the forward angle 8 as the truck body is raised, so that the direction of pull on the hoisting cables, as is presently described will always be parallel to the frame standards 15-15'.

Fixed to opposite sides and lower ends of the standards 15-15' and extending therebetween are plates 26 and 26' and supported thereby, centrally between the said standards is a shaft 27 whereon a large gear wheel 28 is revolvably mounted; the said gear-wheel has a winding drum 29 formed integrally on one side thereof whereon cable sections 30 and 31 are wound, the sections being extended from the drums upwardly over the sheave wheels 17-17' and then downwardly and at their ends are fixed to links 32 at the ends of brackets 33 mounted on the under side and adjacent the forward end of the truck bed 6.

The winding drum 29 comprises a hub portion 34 and spaced drum flanges 35-36-37 forming intermediate guideways 38-39 wherein the cables are wound and which are spaced only at such distance from each other that the guideways 38 and 39 will be of practically the same width as the thickness of the cable sections used, so that, when the latter are wound on the drum, the coils will be formed one upon the other and an even winding will result; it is apparent that by this method, even winding is accomplished and a greater leverage is effected, at the start of a lifting operation, when the greatest weight is placed on the cables and a quicker raising movement is effected after the load has been lifted to such an incline that the weight on the cables is appreciably lessened.

In order to fasten the cable sections to the drum, the central guide flange 36 is pro-

vided with a slot 40 (Fig. V), extending 65 from the edge thereof to a point adjacent the hub of the drum, wherein the cable is seated with the opposite ends of the cable extending into the guideways at opposite sides of the flange. The hub is also built up 70 at the side of the slot, as at 41, in the direction of winding so that the second winding of the cable will be carried evenly to the upper edge of the first winding and when carried thereon no unevenness will result. 75

Supported between the side plates 26 and 26' below the periphery of the gear wheel 28 is a shaft 45 whereon a gear pinion 46 and a larger bevel gear wheel 47, fixed relative to each other, are revolvably mounted; 80 the gear pinion is adapted to travel in mesh with the gear wheel 28 while the wheel 47 operates in an overlapped relation thereto.

Mounted on the outer side of the standard 15 is a shaft bearing 50 and extending 85 revolvably therethrough and through the standard in perpendicular relation to the shaft 45 is a shaft 52 having a bevel pinion 53 fixed on its inner end which is adapted to operate in mesh with the bevel gear wheel 90 47; the outer end of the shaft is extended beyond the side of the frame and is provided with removable crank 54 whereby it may be revolved to actuate the drum wheel to wind or unwind the cables to raise or lower the 95 rear ends of the truck bed frame.

Fixed on the shaft 52 adjacent the bearing 50 is a drum 55 provided with a toothed ratchet surface 56 and at opposite sides with brake surfaces, and pivotally mounted on a 100 pin 57 extending from the bearing member 50 above the shaft 52 is a latch 59 provided at one side with an actuating handle and a tooth 60 which is adapted, on movement of the latch in one direction, to engage the 105 ratchet teeth to check the unwinding of the cables from the drums and at its opposite side has a brake shoe 61 adapted when the latch is moved to its opposite limit to seat against the surface of the drum to effect a 110 braking operation when the body is being lowered from dumping position; the latch tooth and brake shoe are in such relation that when the tooth is in locked relation the shoe is free from the drum and when the 115 shoe is moved to engage the drum, the tooth is freed from the ratchet, but the latch handle is of such weight, or a spring may be attached thereto, so that the tooth is yieldingly retained at all times in contact with the 120 ratchet wheel.

At its outer end the latch has an outwardly extended handle 63 whereby it may be moved from side to side to control movement of the drum as desired.

In Fig. IX, I have shown a style of hoist frame used when a single hoisting cable is employed. The frame standards 51-51'

are here drawn together at their ends and carry a single sheave wheel about which the hoisting cable operates.

Assuming that the hoist is so constructed and mounted and that the cable is fixed to the drum and extended over the sheave wheels and then downwardly and attached at its ends to the brackets beneath the truck frame, if it is desired to move the truck body to dumping position, the operator, by means of the crank 54, revolves the shaft 52 which, through the bevel gears and pinion, revolves the large drum wheel 28 and the cable sections are wound on their respective drums and the rear end of the body is raised accordingly. It is apparent that as the end of the truck body moves upwardly, the hoist frame will pivot on its mounting so that its upper end moves rearwardly under tension of the hoisting cables so that the weight of the body is applied directly longitudinally of the standards and no lateral strain is thrown thereon.

When the body has been raised, it may be locked in this position by moving the latch tooth to locking relation with the ratchet surface. When it is desired to lower the body the latch is moved to its opposite limit and by pressure thereon the brake shoe will be pressed against the drum surface to regulate the speed of unwinding of the cables.

It is apparent that by so constructing the hoist, a very compact arrangement is provided and a minimum amount of space is necessary for its operation; it is also apparent that control of the operating parts is effected through the brake and ratchet parts and the truck bed may be locked at a raised position and lowered under control of the brake to avoid unnecessary jar or damage to the parts.

While I have shown and described the hoist mechanism in combination with a vehicle frame and bed, it is apparent that the hoisting mechanism of this construction could be used for various other purposes without departing from the spirit of the invention:

Having thus described my invention, what I claim as new therein and desire to secure by Letters-Patent, is:

1. The combination with a vehicle frame, and a vehicle bed having one end pivotally mounted on the frame, of a vertically swinging hoisting device, the base of which is resiliently connected to the frame, adjacent to the free end of the bed, and means operating over the upper end of the hoisting device for raising and lowering the bed on its pivoted mounting, the hoisting device having swinging movement toward the bed when the free end thereof is raised and swinging movement away from the bed when the free end of the bed is lowered.

2. The combination with a vehicle frame, 65 and a vehicle bed having one end pivotally mounted on the frame, of a vertically swinging hoisting frame on the vehicle frame, springs connected to the vehicle frame and bearing upon the base of the hoisting frame to yieldingly support it in a vertical position, and means carried by the hoisting frame and connected to the bed to raise and lower the free end thereof.

3. The combination with a vehicle frame, 75 and a vehicle bed having one end pivotally mounted on the frame, of a vertically swinging hoisting frame on the vehicle frame, springs connected to the vehicle frame and bearing upon the base of the hoisting frame to 80 yieldingly support it in a vertical position, winding mechanism carried by the hoisting frame, and cables connected to the winding mechanism and to the bed to raise and lower the free end thereof, the hoisting frame having 85 movement in the direction of the bed when the free end is raised and retractive movement to a vertical position when the free end of the bed is lowered.

4. The combination with a vehicle frame, 90 and a vehicle bed having one end pivotally mounted on the frame, of a vertically disposed hoisting frame on the vehicle frame and having projections extending from opposite edges of the base, means for fastening the 95 hoisting frame to the vehicle frame, said means consisting of springs bearing upon the projections and devices loosely connecting the springs to the vehicle frame, and operating mechanism carried by the hoisting frame 100 and connected to the free end of the pivoted bed.

5. The combination with a frame comprising longitudinally extending side beams and a bed having one end pivotally mounted 105 on said frame, of a hoisting device comprising a frame having a base member seated at its opposite ends on said side beams, bolts fixed at their lower ends in said beams and extending upwardly through and beyond 110 the base member and having heads at their upper ends, springs mounted about said bolts and adapted to bear against said base member and bolt heads to retain the hoisting frame yieldably in vertical position, and 115 means operating over the upper end of the hoisting device for raising or lowering the bed on its pivotal mounting.

6. The combination of the vehicle frame comprising spaced side beams, a vehicle bed 120 pivotally mounted at one end on the said beams, a vertically disposed hoisting frame pivotally supported transversely on the frame adjacent to the free end of the bed, sheave wheels mounted at the upper end of 125 said hoisting frame, a winding drum revolvably mounted within the frame, winding mechanism operatively connected with the wind-

- ing drum and extending to the side of the vehicle frame, cables extending over said sheave wheels and fixed at their opposite ends to the vehicle body and to the winding 5 drum, yieldable members fixed to the frame beams for normally retaining the hoist frame in vertical position and for yieldingly permitting pivotal movement thereof accordingly as the vehicle body is raised.
- 10 7. The combination with a vehicle frame comprising longitudinally extending side beams and a vehicle body pivotally mounted at one end on said side beams and freely supported at its opposite end, of a hoist frame 15 located adjacent the free end of the bed comprising base beams supported at their ends on the frame side beams, spaced standards, mounted vertically on said base beams, sheave wheels mounted at the upper ends of 20 said standards, connecting plates secured to opposite faces of said standards, a shaft supported by said plates between the standards, a gear wheel revolvably mounted on said shaft and having a winding drum fixed 25 thereon, cables extending over said sheave wheels and fixed at their opposite ends to the free end of the vehicle body and to the winding drum, a winding shaft mounted in one of the standards extending to the side 30 of the vehicle frame and having geared connection with the drum gear wheel and operable to actuate the drum to wind the cables thereon and yieldable members having fixed relation to the vehicle frame bearing against 35 the hoist base beams to retain the hoist frame normally in vertical position and permitting a rearward pivotal movement of the upper ends of the standards according to the pivotal movement of the vehicle body.
8. The combination with a vehicle frame 40 comprising longitudinally extending side beams, and a vehicle body pivotally mounted at one end of said side beams and freely supported at its opposite ends, of a hoist frame pivotally mounted on the vehicle 45 frame comprising base plates, standards mounted vertically in spaced relation on the base plates, a transverse shaft mounted at the upper ends of said standards, sheave wheels revolvably mounted on the said shaft, 50 face plates fixed to the opposite sides of standards and extending therebetween, a shaft mounted by said face plates centrally between the standards, a geared wheel revolvably mounted on said shaft, a winding 55 drum fixed concentrically to said gear wheel, cables extending over said sheave wheels and fixed at their opposite ends to the free end of said vehicle body and to said winding drum, a second shaft mounted between said 60 plates, a beveled gear wheel revolvably mounted on the second shaft, a gear pinion fixed concentrically to the bevel gear wheel and operating in mesh with the drum gear wheel, a shaft extended through one of the 65 standards, a bevel gear wheel fixed to the inner end of said shaft operating in mesh with the first named bevel gear wheel, a crank at the outer end of the shaft, yieldable members fixed to the vehicle frame 70 and bearing against the hoist base beams to retain the frame in vertical position and to allow it to pivot according to the upward movement of the vehicle body about its pivotal point.

In testimony whereof I affix my signature.

WINFIELD S. LIVENGOOD.
